UNITED STATES PATENT OFFICE.

SAMUEL D. GLOSS AND WILLIAM WRIGHT, OF CHICAGO, ILLINOIS, ASSIGNEES, BY MESNE ASSIGNMENTS, TO CHICAGO-CLEVELAND CAR ROOFING COMPANY, OF CHICAGO, ILLINOIS, A CORPORATION OF DELAWARE.

CAR ROOF.

Application filed October 14, 1924. Serial No. 743,550.

This invention relates in general to improvements in freight car roofs and more particularly to improvements in car roofs of the type generally designated as outside metal roofs, which outside metal roof covers the inner wooden roof sheathing of the car.

Objects of the invention are the provision of a roof construction which will effectively resist the tendency of movement of the roof structure so that a metallic roof may be applied and held thereon in such a manner that the roof sheets will not move or float thereon with attendant chafing of the light gauge metallic parts; the provision on such a roof construction of roof sheets extending from eaves to eaves and having side flanges engaging an anchor arranged at each eaves end of the side flanges so that the anchors hold the roof sheets down on the roof structure, said side flanges and anchors being enclosed by side seam caps; the provision of such a car roof construction permitting slight movement of the metallic roof sheets should there be any movement of the wooden roof sheathing; the provision of such a roof which is simple to manufacture at a reasonable cost and which can be applied without the necessity of specially skilled workmen and which when so applied will be weathertight and not require frequent repair and replacement; and such other objects and advantages of the invention as may be found to obtain in the structure herein-after set forth and claimed.

In the accompanying drawings forming a part of this specification and showing, for purposes of exemplification, a preferred form and manner in which the invention may be embodied and practiced, but without limiting the claimed invention specifically to such illustrative instance or instances:

Figure 1 is a top plan view, parts being broken away for better illustration, of a car roof embodying the invention.

Fig. 2 is a side elevational view of a portion of the same.

Fig. 3 is a diagrammatic view taken transversely of the car, illustrating the position and arrangement of the roof sheets when assembled on a car.

Fig. 4 is a vertical cross-sectional view taken on the line 4—4 of Fig. 1.

Fig. 5 is a top plan view of a portion of an eaves corner of a roof sheet.

Fig. 6 is a vertical sectional view taken 55 on the line 6—6 of Fig. 1.

Fig. 7 is a vertical cross-sectional view taken on the line 7—7 of Fig. 1.

Fig. 8 is an end elevational view taken at the eaves end of a side seam cap.

Fig. 9 is a top plan view of the same.

Fig. 10 is a top plan view of one of the anchors.

Fig. 11 is an end elevational view of the same.

Fig. 12 is a side elevational view of the same.

Fig. 13 is a vertical cross-sectional view taken on the line 13—13 of Fig. 1.

Fig. 14 is a top plan view of Fig. 13, parts 70 being broken away, taken at the ridge over the side flanges.

Referring to the drawings, the upper part of the car-body, which is the supporting frame work for the roof, consists of wooden 75 side plates 10 having their top surface curved, and, in the present instance, wooden purlins 11 and wooden ridge pole 12. Secured to the outer face of the side plate is the wooden side sheathing 13, the top surface of which is flush with the top surface of the side plate. Secured on the side sheathing at the eaves edges of the roof are the wooden side fascia 14, the top surface of which is flush with the top surface of the 85 side sheathing. The inside wooden roof sheathing 15, consists of wooden roof boards 16, extending diagonally across the car, as shown more particularly in Fig. 1, and curved to conform to the desired curvature 90 of the roof. These roof boards 16 are each provided with a slot or groove 17 in one side edge and a tongue 18 in the other so that when laid on a car the tongue engages in the slot of the next adjacent board so 95 that when the matched boards are in place they tend to hold each other from movement and rigidify the roof structure as a unit. The shorter boards at each end of the car are secured to the side plates and end plates 19, and the longer ones are secured at each extremity to the oppositely disposed side plates by suitable fastenings such as by 100 nails 21.

The diagonal arrangement of the roof boards when matched as described, in a structure of arched configuration, and secured at the ends, as above described, results in a 105

structure which so effectively braces the car that the weaving and other movements of the car are negligible and the construction provides a very substantial rigid roof.

5 Metallic roof sheets 22, of light gauge metal, formed to conform to the curvature of the roof, are secured on the wooden roof. These sheets extend from eaves to eaves and are flanged at each side to provide flanges 23, 10 which extend clear across the car, consisting of an upwardly extending and inwardly inclined portion 24 rebent at 25 to provide a depending flange 26 spaced from the main body 27 of the roof sheet and also spaced 15 from the upwardly projecting portion 24. The eaves edges of the wooden roof sheathing are gained out at 28 to receive a metallic flashing 29 having at its inner edge an upwardly projecting outwardly rebent portion 20 30, the upper surface 31 of which is in a plane beneath the plane of the top surface 32 of the inside wooden roof sheathing. The outer edge of the flashing is bent downwardly at 33 to enclose the edges of the roof 25 sheathing and is then bent outwardly at 34 over the top surface of the side fascia and terminates in a depending flange 35 secured to the outer surface of the side fascia. The eaves edges of the roof sheets are flanged 30 downwardly and outwardly at 36, and terminate in an outwardly pressed longitudinally extending rigidifying bead 37 which is spaced from the portion 34 of the flashing. The side flanges of the roof sheets stop 35 short of the eaves edge of the roof sheets as indicated at 38 (Fig. 5) to facilitate application of the roof sheets.

An anchor is secured at each eaves edge of the car between each two adjacent roof 40 sheets, said anchor consisting of two horizontal base portions 39 that are secured to the car by nails 39' or other suitable means. The base portions are pressed upwardly at 40 to form a bearing for the adjacent side 45 edges of the roof sheets, and these portions 40 are bent upwardly to form vertical contacting members 41 having outwardly extending oppositely disposed horizontal holding down portions 42 connected by a curved 50 top 43. The portions 42 engage over the side flanges of adjacent roof sheets where the flanges are rebent at 25 and hold the roof sheets, at the eaves, down on the wooden inside roof.

55 The sides of adjacent roof sheets are enclosed by two side seam caps 46, which are tubular in cross-section and have curved sides 47 bent inwardly at 48 and terminating in upwardly extending flanges 49 which 60 engage in the space between the portions 24 and 26 of the side flanges of adjacent roof sheets, more clearly shown in Fig. 6.

The eaves ends of the side seam caps are closed by folding the top portion down at 65 51 and folding the sides laterally as at 52

over the part 51. At the ridge ends the sides of the cap are cut away and the top continued to form extensions 53 that are lapped one over the other as indicated at 55 and the lapped extensions are capped by 70 an inverted U-shaped cap 56 having lateral flanges 57 extending transversely of the car. The lapped ridge ends of the side seam caps are secured together and to the inside wooden roof by a bolt 58 that passes through 75 apertures in the cap 56, lapped extensions 55, the wooden inside roof sheathing and the ridge pole. At its upper end, the bolt 68 passes through an aperture in the running board saddle 59 to secure the saddle to the 80 roof. The saddles support the usual running boards 60 and are channeled at 61 on their under side to fit over the side seam caps hereinabove described. The side flanges of the roof sheets are cut away at 85 61' and the remaining portions pressed to form offsets 62 to permit easy passage of the bolts 58 between adjacent roof sheets.

At each end of the car, wooden mullions are provided, said mullions being enclosed 90 by mullion caps having a depending flange 63 secured to the end of the car and having an inner side flange 66 similar to one flange of the side seam caps hereinabove described. The eaves ends of the mullion caps are 95 closed by a depending flange 67.

One way of assembling the metallic roof onto the inside wooden roof sheathing is to first tilt the mullion cap 68 and end roof sheet 69 so that their side flanges may be 100 interlocked and then lay them down on the roof, then raise the right-hand side 70 of roof sheet 69 and nail the anchors in place, then tap the anchors on the side toward the roof sheet 69 and lay the roof sheet down 105 so that the top 25 of the side flange rests under the holding down portion 42. Then tap the anchors on the other side and lay the next sheet on the car so that the portion 25 of that sheet fits under the portion 42 and so continue throughout the length of the car. Then the side seam caps are slid on the adjacent side flanges in the direction of the ridge until the extensions 55 are lapped. Then apply the cap 57 and the running 110 board saddle 59. After the saddles are applied then the bolt 58 is passed through the saddle 59, cap 57, lapped extensions 55, roof sheathing 15, and ridge pole 12 and secured, 115 preferably by a washer and a nut 72, to the lower face of the ridge pole.

The invention as hereinabove set forth is embodied in a particular form of construction but may be variously embodied within the scope of the claims hereinafter made.

We claim:

1. A car roof comprising, in combination: side plates; an inside roof of wooden boards; a flashing secured at the eaves edge of the roof boards extending longitudinally of the 130

car, roof sheets having side flanges and eaves flanges arranged in a plane beneath the plane of the main body of the roof sheets; anchors arranged between the eaves 5 edges of the side flanges of adjacent roof sheets and secured to the flashing below the general level of the roof sheets, each of said anchors having an offset portion providing a bearing for the roof sheets and having a 10 portion engaging the side flanges of the sheets for holding them down on the wooden roof; seam caps enclosing the side flanges of adjacent roof sheets and the anchors arranged therebetween, said seam caps being 15 lapped at the ridge and secured to the roof structure.

2. A car roof comprising, in combination: a wooden substructure, said wooden substructure being gained out at the eaves edge 20 and a metallic flashing secured in said gained out portion; roof sheets extending clear across the car, said roof sheets having side flanges extending across the ridge and having eaves flanging, the side flanges terminating at the eaves of the roof; anchors arranged between the side flanges of adjacent sheets, and secured to the roof in the gained out portion thereof, each of said anchors having a portion spaced upwardly from said 25 gained out portion providing a bearing for the roof sheets and also having a portion engaging the adjacent roof sheets for limiting their movement and for holding them down on the substructure, and side seam caps loosely connected with and enclosing the side 30 flanges of each of the adjacent roof sheets and the anchors therebetween.

3. An anchor for use in car roofs com-

prising a curved top bent inwardly at each side to provide holding down portions, said 40 inwardly bent portions being bent downwardly, said downwardly bent portions making contact with each other and being bent outwardly to provide bearing portions, said bearing portions being bent downwardly and 45 outwardly to form seating portions.

4. An anchor for use in car roofs comprising a top bent inwardly at each side to provide holding down portions, said 50 inwardly bent portions being bent downwardly, said downwardly bent portions being bent outwardly to provide bearing portions, said bearing portions being bent outwardly and downwardly to form seating portions.

5. An anchor for use in car roofs comprising upper holding down portions and lower bearing and securing portions and a web connecting the upper and lower portions.

6. A car roof comprising roof sheets having side flanges extending upwardly and then bent back inwardly, anchors arranged between the flanges of adjacent sheets and provided with upper portions extending over and engaging the upper portions of the 65 flanges on the roof sheets and lower portions supporting the flanged edges of said roof sheets for securing the same in proper position, said lower portions of the anchors being provided with downwardly offset portions for receiving securing means.

In witness whereof we have hereunto affixed our names.

SAMUEL D. GLOSS.
WILLIAM WRIGHT.
